(57) CLAIM

I claim the ornamental design for a table, as shown and described.

DESCRIPTION

FIG. 1 is a perspective view of a table, showing a first embodiment of my new design;

FIG. 2 is a first side view of the table of FIG. 1;

FIG. 3 is a second side view of the table of FIG. 1;

FIG. 4 is a front elevation view of the table of FIG. 1;

FIG. 5 is a rear elevation view of the table of FIG. 1;

FIG. 6 is a top plan view of the table of FIG. 1;

FIG. 7 is a perspective view of a table, showing a second embodiment of my new design;

FIG. 8 is a first side view of the table of FIG. 7;

FIG. 9 is a second side view of the table of FIG. 7;

FIG. 10 is a front elevation view of the table of FIG. 7;

FIG. 11 is a rear elevation view of the table of FIG. 7;

FIG. 12 is a top plan view of the table of FIG. 7;

FIG. 13 is a perspective view of a table, showing a third embodiment of my new design;

FIG. 14 is a first side view of the table of FIG. 13;

FIG. 15 is a second side view of the table of FIG. 13;

FIG. 16 is a front elevation view of the table of FIG. 13;

FIG. 17 is a rear elevation view of the table of FIG. 13; and,

FIG. 18 is a top plan view of the table of FIG. 13.

Portions of the table shown in broken lines are for illustrative purposes only and form no part of the claimed design.

1 Claim, 12 Drawing Sheets
